UNITED STATES PATENT OFFICE.

HERMAN C. NICHOLAUS, OF DETROIT, MICHIGAN, ASSIGNOR TO JOHN W. CRAIG, OF DETROIT, MICHIGAN.

CONTROLLING MECHANISM.

1,116,908.

Specification of Letters Patent.

Patented Nov. 10, 1914.

Application filed March 13, 1912. Serial No. 683,445.

To all whom it may concern:

Be it known that I, HERMAN C. NICHOLAUS, a citizen of the United States of America, residing at Detroit, in the county 5 of Wayne and State of Michigan, have invented certain new and useful Improvements in Controlling Mechanism, of which the following is a specification, reference being had therein to the accompanying 10 drawings.

In the operation of certain types of smoke consumers for furnaces or boilers and any other like apparatus, it is frequently necessary or desirable that steam be injected into 15 the combustion chamber over the fuel during the initial moment of combustion after fresh fuel has been placed therein or that the door to the combustion chamber be closed gradually to admit air over the fuel 20 bed to furnish oxygen for the freshly generated gases. Valves controlling such steam jets are frequently arranged to be opened by the operation of the fire door and various devices have been used to automatically 25 and gradually close such a valve after the fuel door is closed or while it is being closed so as to prolong the period of the injection 30 of the steam, or to close the door itself either separately or with the valve.

This invention relates to means for automatically controlling a valve, fire door, or damper to close the same gradually within a predetermined period, and more particularly to a device of this character adapted 35 for use as above described, the invention including means for carrying the period of operation of the mechanism to meet different requirements of service.

The invention consists in the matters hereinafter set forth, and more particularly 40 pointed out in the appended claim.

In the drawings, Figure 1 is a view in front elevation, partially broken away and with the outer casing removed, of a device 45 that embodies features of the invention, and Fig. 2 is a view in longitudinal section of the mechanism.

As herein indicated a plate 1 of suitable 50 design and material for attachment to a furnace or the like, supports a removable housing or casing 2. A rack bar 3 is reciprocable longitudinally on a main frame 4 mounted on the base plate, any convenient means, as for example, a stud 5 passing 55 through a guide slot in the frame holding

the bar in alinement. The lower end of the bar which extends beyond the housing 2, is adapted to be secured to a push rod 6 that is so connected to a furnace door, or the like that when the latter is opened the bar is 60 moved to the position indicated. An actuating weight 7 of suitable material is suspended from the lower end of the bar or other suitable place. The push rod is also arranged to close the door when the weight 65 moves the rack bar back, and also if desired, a valve in the steam supply pipe through any suitable connections.

A main drive pinion 8 is journaled on a stud 9 in the main frame to mesh with the 70 rack bar and has a ratchet wheel or step 10 which is adapted to drive a follower gear 11 when the rack bar moves outwardly, through the medium of a suitable dog or pawl 12 having a lug 13, engaging the 75 ratchet, a spring finger 14 yieldingly holding the dog in position. Preferably the gear 11 is journaled on the stud 9 with the dog pivoted on the outer face of the gear and the lug 13 extending through the opening of the 80 wheel.

A governor brake spindle 15 is journaled on the upper part of the frame 4 and is operatively connected to the gear 11 by any suitable means, as for example, a pair of 85 beveled gears 16 operating an arbor 17 which in turn is coupled through a reduction train indicated at 18 whose initial pinion 19 meshes with the gear 11.

A friction plate or disk 20 that is longitudinally reciprocable on the spindle 15 and is keyed to rotate with the latter, is normally forced downward by a spring 21 encircling the spindle in compression between the plate and the lower end of a thrust bearing stud 22 or the like, against the action of a pair of governor weights 23 hung by arms 24 to swing and revolve with the spindle and coupled by links 25 to the disk 20 to force the latter up when the centrifugal action of the weights thrusts them out. A suitably disposed brake limits the distance to which the friction plate may be raised by the action of the governor. Preferably such stop is a stud 27 screwthreaded through the arm of the frame so as to bear against the disk when the latter rises. Adjustment of the stop or brake is had by the insertion of a wrench or suitable tool through an opening in the casing 2 closed by a guard 110

cap. The push rod 6 by which the rack bar is moved to its upper limit is also operatively connected to any valve, damper or door that it is desired to control so that downward movement of the rack bar under the pull of the weight 7 gradually closes the same. In operating the device the brake for the governor disk is so adjusted that the governor's rate of rotation is regulated by the applied friction whereby, when the weight is raised and released, it can move the rack bar back again only as fast as the governor allows the train driven by the rack to turn. As a consequence the mechanism may be made to close the valve, the furnace door or the like as rapidly or slowly as needed. As there are no springs whose temper can be effected by furnace heat, the device is particularly adaptable for the purpose noted and when once adjusted can be relied upon to control the door or valve as desired.

Obviously, changes may be made in the details of construction without departing from the spirit of the invention and I do not care to limit myself to any particular form or arrangement of parts.

I claim:

In a controlling mechanism, the combination with a casing, of a vertically recipro-

cable rack bar extending into the lower end 30 of said casing, a weight detachably connected to the lower end of said rack bar, a frame arranged within said casing, a pinion revolvably supported from said frame and meshing with said rack, a ratchet wheel forming 35 part of said pinion, an apertured gear wheel revolvably supported adjacent to the ratchet wheel of said pinion, a spring pressed pawl carried by one side of said gear wheel, a lug carried by said pawl and extending through 40 one of the apertures of said gear wheel to engage said ratchet wheel whereby movement can be imparted to said gear wheel by an outward movement of said rack bar, a train of gears supported by said frame and operated by a movement of said gear wheel, and a governor supported by said frame 45 above said train of gears and having connection therewith to control the operation of said train of gears and a movement of said 50 rack bar out of said casing.

In testimony whereof I affix my signature in presence of two witnesses.

HERMAN C. NICHOLAUS.
